UNITED STATES PATENT OFFICE.

RALPH STORM; JOSEPH F. UNDERWOOD, AND ROBERT JACKSON, OF WATERLOO, IOWA.

REGISTERING DEVICE.

No. 874,635.

Specification of Letters Patent.

Patented Dec. 24, 1907.

Application filed May 10, 1907. Serial No. 372,367.

To all whom it may concern:

Be it known that we, RALPH STORM, JOSEPH F. UNDERWOOD, and ROBERT JACKSON, citizens of the United States of America, and residents of Waterloo, Blackhawk county, Iowa, have invented certain new and useful Improvements in Registering Devices, of which the following is a specification.

10 Our invention relates to improvements in registering devices, and the object of our improvements is to provide registering mechanism to be used in railway stations in connection with train signals, whereby a record 15 may be made and kept of passing trains and of their stopping for orders. This object we have accomplished by the mechanism which is hereinafter fully described and claimed, and which is described in the accompanying 20 drawings, in which—

Figure 1 is a diagrammatic side elevation of our improved registering device, with one side of the casing removed, showing the same operatively connected with a semaphore signaling mechanism. Fig. 2 is a front elevation of the registering device with the front part of the casing removed, and showing a pair of such devices cased beside each other but otherwise independent of each other. 25 Fig. 3 is a detail perspective view of that part of the apparatus which contains the circuit-closing device and disk lock. Fig. 4 is a detail view of a portion of the record tape, showing its rear side. Fig. 5 is a diagram of 30 the electric circuits between two stations. Fig. 6 is a detail view of a portion of the record tape and its slotted casing. Fig. 7 is a detail view of the method of wiring between a station registering device and the 35 registering devices of the stations on either side. Fig. 8 is an enlarged detail view depicting that part of the apparatus used for producing a punctured record on the tape. Fig. 9 is an enlarged detail view of the toothed 40 guard in operative contact with the record tape.

Similar reference characters refer to similar parts throughout the several views.

Our device is particularly intended to operate as a check against both trainmen and station operators. Its action is positive in use to record the movements of passing trains, and its absence of a record will also positively disclose the fact that a train crew 55 has improperly run by a stop-signal. A check is provided against attempts of an op-

erator to remove evidences of his default, as the action of an operator at another station is requisite in order to close the electric circuit used for actuating mechanism to unlock the 60 recording device. Other checks are provided against effective tampering with the apparatus to change or improperly make a record. A record properly made will infallibly disclose the fact of a train, stopping 65 for orders, or of its running by a properly placed signal contrary to the rules.

The mechanism of each registering device is closely incased at each station in a box. The box has two compartments *a* and *b*, 70 separated from each other by a partition, there being no communication between said compartments. A complete registering instrument is placed in each compartment, the instrument in the compartment *a* being 75 placed in electrical circuit with a similar instrument *b'* located in a station to one side, while the instrument in the compartment *b* is likewise placed in an independent electrical circuit with a similar instrument *a'* located to the other side of the initial station, the first pair of instruments *a* and *b'* coöperating for signaling trains moving in either direction between the initial station and the station to its left, while the instruments *b* and 85 *a'* coöperate in the same way. The wiring used between any pair of such coöoperating instruments is shown in Fig. 5, while the complete wiring circuits between such pairs of instruments as used between the initial station and the nearest stations on either side for trains moving in either direction, is disclosed in Fig. 7.

Our improved registering device may be used in connection with any approved form 90 of signaling device, but for purposes of illustration it is depicted as being operatively connected with a semaphore-signal located outside the station so as to be seen from an approaching train.

The semaphore 50 is attached to a lever 49 which is medially pivoted on a bolt 52 set in uprights on the post 51. The end of the lever 49 has an orifice to receive the upper end of the vertical rod 48, and has a small 105 amount of play thereon between nuts secured thereto. The lower end of the rod 48 is supplied with a weight 47 adapted to exercise a stress upon the semaphore to normally keep it extended in its horizontal signaling position, the end of said rod below the weight 110 having a pivotal connection at 46 to the lever

41—42, the latter pivoted at 43 to some fixed body. The lower end of the bell-crank lever 41—42 is pivoted at 45 to a link 40, which in turn is pivoted to the lower end of the bell-5 crank lever 38—37, the latter pivoted at its angle to some fixed body, and having its upper member 37 pivoted to the lower end of a pitman 36, whose upper end is pivoted on a crank-stud 35 connected between the disks 10 53 and 4. The disk 53 is fixed to the shaft to which the outer and smaller disk 69 is fixed, said shaft and disks being rotated by means of the crank 33 outside of the casing-box. The crank-stud 35 causes a like rotation of 15 the innermost and largest disk 4, the latter being mounted on a stud shaft 71 projecting from a bearing in the partition of the casing.

The numeral 13 denotes a pawl pivoted to a stud on the inner face of the casing, and 20 adapted to engage with the single notch 34 in the outer disk 69 at a certain position on its circumferential edge, whose use will be explained later.

To the inner face of the innermost disk 4 25 near its edge is attached a boss 14, adapted to enter the path of the reciprocating plunger 8 and move the latter outward at a certain moment in the action of the device, the plunger having an anti-friction roller 7 thereon to furnish a frictionless contact with said boss. At a predetermined point on the circumferential edge of the disk 4 a large right-angled notch 5 is located to receive the contacting lower corner of the slider 1. This 30 corner is supplied with an anti-friction roller 6 to insure frictionless contact with the edges of the notch 5 in the disk 4. The forward portion of the slider passes through an orifice in the front of the casing and is supplied with 35 a push-button-head. The rear portion of said slider is bent upwardly and then rearwardly in a horizontal member 2 the vertical upward movement of the latter being limited by a stop 3. The upwardly bent 40 portion of said slider has a forwardly extending branch 28 which forms a stop for the vertical slider 54 when the latter is in its lowermost position. Referring to Fig. 3, it will be seen that the slider 54, which moves in a bearing opening in the fixed block 32, is surrounded by an armature 25 adapted to be attracted to and move into contact with the poles of an electro-magnet 24—68 in the usual manner. An angularly bent arm 29 45 extends from the lower part of the slider 54, and when the latter moves upward drawn by the electro-magnet is received within a slot 65 in said block 32. The outer end of the arm 29 has a short upwardly-extending member 63 received within a staple or loop 64 on said block 32. Pivotedly mounted in bearings in the front casing and in the block 32 is a short rock-shaft 67, whose outer end without the casing is furnished with a crank 50 65 26. The intermediate portion of said shaft

has a laterally projecting arm 62 furnished with insulated electrodes 59 and 61 adapted to contact with the electrodes 57 and 58 mounted in the block 32 when the arm is in its lowermost position, and thus close a circuit to be hereinafter described. When the crank 26 is rocked over in the reverse direction the electrodes 61 and 59 come in contact with the fixed electrodes 55 and 56 mounted in said block 32 on the opposite side of the 75 shaft. A short arm bearing a counterweight 31 is laterally extended from the shaft directly opposite to the arm 62, and tends to keep said arm 62 elevated out of contact with the electrodes in the block 32. The up-turned member 63 of the arm 29, in a certain position of the slider 54 acts as a stop for the arm 62 preventing the latter from arriving at its lowermost position to effect contact between the electrodes thereon and those on 80 the block 32 thereunder. When the slider 1 is in the position indicated in Fig. 1, its rear-most lower corner is locked into the notch 5 in the disk 4, effectually preventing rotation of the latter. The slider 1 cannot be moved 90 forward so as to clear said notch and permit rotation of the disk 4, unless the circuit is closed through the electro-magnet 24, thus elevating the armature 25 with its attached slider 54, so that the lower end of the latter 95 will pass from the path of the member 2. When the slider 1 is drawn forward, the mechanism is in readiness to perform a registration, which may be of two kinds as hereinafter described.

In the inner front lower corner of the box 100 is a small receptacle or boxing in which is mounted a rotatable spool 15 enwrapped with a supply of thin paper tape 16. This tape, as depicted in Fig. 4, may be of uniform length with other tapes of the kind, and have its rear surface printed with large characters or other arbitrary devices in order to divide it into a predetermined number of spaces of equal lengths differently designated, to prevent alteration or defacement 105 to change a certain record thereon. Each station is given some arbitrarily determined character or characters 111, such characters being written or printed on each equal division of the rear surface of the tape. This countersigned character on each division is a further safeguard against alteration or substitution of the tape. The tape 16 is conducted out of the boxing through a narrow 110 slot and between the rollers 108 and 109 and between toothed guard-combs 103 into a flattened conduit 18. The combs 103 have sharp teeth 110, and are mounted opposite each other on pivoted studs 107 so that the 115 teeth bear against each other with the thin tape 16 between them. It is obvious that any attempt to tamper with such tape by drawing it down would be futile, as the sharp teeth 110 would in that event engage the 120

125 130

tape and sever it. The combs 103 however do not interfere with the upward movement of the tape. The tape after leaving the conduit 18, passes between friction-drums 93 and 95, and thence forward through a narrow slot in the casing and a flat conduit 94 secured therein into a box 23, whose front may be made of glass if desired, but such front being hinged at the bottom, cannot be lowered ordinarily on account of the catch 22 engaging the hook 78 on the forward end of the lever 92, the latter fulcrumed at 91 to a bearing projecting from the inner surface of the box cover. The inner end of said lever has an upwardly projecting arm pivoted thereto and extending through an orifice in the box cover, whereby said lever may be depressed at its rear end to elevate its forward end to release the hook 78 from the catch 22. However, the inner end of the said lever has a depending knife-edge 20 adapted to be received into a socket 21 secured to the front of the casing immediately below the front opening of the conduit 94, the tape 16 passing between such knife and socket, and any attempt to open the box 23 to withdraw the tape, will result in severing such tape if the arm 19 be depressed.

30 The friction-drums 93 and 95 have each opposed to each other two rings of minute teeth which slightly puncture the tape and assist in drawing it up, and the parallel punctures thus made in the tape help to prevent alteration of the record thereon. The drum 95 is mounted as an idler, but the opposed drum 93 has at one end a flange provided with gear-teeth 30, the latter adapted to intermesh with the similar gear-teeth on the gear-wheel 99, both the drums 93 and 95 and the wheel 99 being mounted on shafts extending from bearings in the casing. Attached to the outer side of the gear-wheel 99 is a small ratchet-wheel 100. A short bar 97 is pivoted at its forward end to a stud 96 on the slider 1, and is provided on its upper side with several teeth 98 adapted to engage the teeth of the ratchet-wheel 100 when the slider is moved backward, but to slip over when the slider is moved forward, a light compression-spring 102 keeping such bar in contact with said ratchet-wheel. When pushed backward once the slider 1 by means of this train of gearing induces the movement of the tape 16 to an extent equal to one of its regular subdivisions.

35 As shown in Fig. 6, an aperture 17 is placed at a convenient place in the front part of the casing immediately over the tape 16 in the flat conduit 18, but immediately over the cutting forward end 10 of the plunger 8, and such orifice is provided for the use of the operator, it being the intention that at certain regulated times or at the beginning 40 of a day's business, he shall mark it through such aperture with his station character and the date. An arm 73 extends downwardly from the slider 1 and has a forwardly bent punch 11 set horizontally opposite to the punch 10 on the plunger 8, so that when both are used for making one record the plunger 10 will perforate the tape on a record portion 77 at 76 opposite to the puncture 75 made by the punch 11. The punch 11 can only make a puncture in the tape 16 when the slider 1 is released and drawn forward, and the plunger can only record its puncture when the released disk 4 has been rotated a sufficient distance to cause its boss 14 to drive said plunger forward within its 45 bearings 12. Small compression springs 105 and 9 are used to exercise a backward traction on the punches 11 and 10 respectively. A short distance below the punches referred to, is a slot in the casing at 104, a curved guide-plate 106 extending into it to convey therethrough the clippings made by the punches in making the punctures in the tape 16, said punches moving through an opening in the conduit 18 and between a 50 plate 105 attached thereto and the plate 106.

Our improved device is operated in the following manner. In the event that a train is approaching a station having the device *a*—*b* therein from the west, as indicated 55 by the arrow in Fig. 7, and is about to pass said station, the operator therein having his semaphore 50 in the up or warning to stop position, as indicated by the full lines in Fig. 1, in the event that said operator has no orders requiring a stop and desires to lower the semaphore to its position indicated by the dotted lines to permit the train to pass without stopping, he must first notify the operator at the station next to the east by telephone or telegraph to give him his assistance in completing an electrical circuit through the device before an adjustment of the mechanism can be made to lower said signal. As will be seen by reference to the diagrams in 60 Figs. 5 and 7, each circuit is broken in two places, for instance, in the case hereinbefore supposed, one break in the circuit will be in box *a* and the other in box *a'* at the station to the east thereof. The break in each case 65 occurs in that part of each mechanism between the electrodes 59 and 61 on the arm 62, and the electrodes 57 and 58 or 55 and 56 set in the block 32. This being the case one operator cannot close the circuit himself, but 70 requires the assistance or connivance of another operator at a distant station to effect the purpose. When the operator at the device *b'* has been notified to give the circuit, he closes the break at his end by rocking the 75 shaft 67 so that the bar 62 will move downward and cause the electrodes thereon to contact with the electrodes 157 and 158 (the latter corresponding with the electrodes numbered 57 and 58 in Fig. 3), which closes 80

the circuit through the electro-magnets 24, and the armature 25 is drawn up with its slider 54, the latter moving out of the path of the horizontal slider 1, the stop 63 also moving up and preventing any circuit being made through the other electro-magnet at the easterly station. When the slider 1 is free, the operator at *a* draws it forward, at the same time removing the corner of 1 from the notch 5, and also making a record 76 on the proper subdivision 77 of the tape 16 with the punch 11. At this juncture, said operator turns the crank 33 rotating the disk 69 till the pawl 13 engages the notch 34, and the movement of the disk 53 actuates the lever 36, and the intermediate connections between said lever and the semaphore 50, lowering said semaphore, thus signaling the approaching train to pass, the block being clear ahead, and no orders to stop. The continued rotation of said crank causes the disk 4 and its boss 14 to also rotate until said boss contacts with and drives forward the plunger 8, causing its punch 10 to make a record 75 on the opposite side of the subdivision 77 of the tape 16, and the two records on one subdivision thus indicate the fact that the train was allowed to pass without orders, and that the semaphore was duly lowered. The continued rotation of the disk 4 again brings the notch 5 to its former position, where the spring 105 causes the slider to again contact with said notch, and the circuit being broken through the electro-magnet, the slider 54 again locks the slider 1 against the notch. A pawl 112 is pivoted to the casing and serves to engage the notch 34 in the disk 69, and prevent any attempt of the operator to tamper with the mechanism, by trying to reverse the rotation of the disks to change the position of the semaphore arm 50 without a record being taken. When the slider 1 is pushed back by the spring 105, its connected toothed bar causes a rotation of the train of gears and the toothed drums, and moves up the tape 16 to uncover another subdivision 77 for record. When the semaphore remains up, and the approaching train stops for orders, before the operator can give a clearance card he has to assure himself that the block ahead is clear, and he does this in the following way. He calls up the operator at the next station ahead, and if the block is clear ahead the latter operator closes the circuit in the manner hereinbefore described. The first operator then pulls out the released slider 1, thus making a record on the tape with its bracketed punch 11, and this record by itself then indicates that the operator has properly ascertained that the block ahead is clear and is his record authority for issuing a clearance card. In the event that a train should run by a raised semaphore, the coincidence of a blank record 65 on the tape with the failure of the trainmen

to produce a clearance card would be conclusive as to their default. If the operator improperly lowers the signal and allows the train to pass the tape record will fix the responsibility on him. In either event, a 70 check is placed upon both the station operator and the train crews, and a record made which cannot be successfully tampered with without the certainty of detection.

Having described our invention, what we 75 claim as new, and desire to secure by Letters Patent, is:—

1. A device of the character described, consisting of an electrical circuit between two stations, an electro-magnet inserted in 80 said circuit at one station, a make-and-break device inserted in said circuit at the other station, a semaphore-signal device at the former station, means at the same station for actuating said semaphore-signal device, 85 locking-means operatively engaged between the armature of said electro-magnet and said semaphore-actuating means adapted to lock the latter in one position, recorders separately connected with the said locking- 90 means and with said semaphore-actuating means adapted to independently record the action of their said connections on a tape, a movable tape adapted to receive successive records from said recorders, and inclosures 95 for said tape adapted to prevent alterations in the records impressed therein.

2. A device of the character described, consisting of an electrical circuit between two stations, an electro-magnet inserted in 100 said circuit at one station, a make-and-break device inserted in said circuit at the other station, a semaphore-signal device at the former station, means at the same station for actuating said semaphore-signal device, 105 locking-means operatively engaged between the armature of said electro-magnet and said semaphore-actuating-means, a movable tape, means for progressively moving said tape in connection with said locking-means, 110 and recorders separately connected with said locking-means and with said semaphore-actuating-means adapted to independently record the action of their said connections on said tape.

3. A device of the character described, consisting of two electrical circuits between separated stations, a make-and-break device in each circuit at each station, an electro-magnet in one circuit at one station, an 120 electro-magnet in the other circuit at the other station, a semaphore at each station, means at each station for actuating its semaphore, locking-means at each station adapted to lock its semaphore in one position and 125 adapted to be released only by the adjacent electro-magnet connected thereto, when the circuit is closed through said device by the use of both of the make-and-break devices at 130 said stations, and means at each station con-

nected to said locking-means and to said semaphore-actuating-means independently adapted to record the action of either of said connections.

5 4. A device of the character described, consisting of an electrical circuit between two stations, an electro-magnet inserted in said circuit at one station, a semaphore-signal device at the same station, a rotatable 10 disk having engaging means thereon and operatively connected with said semaphore-signal device, a slide adapted to lock into said engaging means when in a predetermined position, an armature adapted to engage and lock said slide into its said predetermined position when the circuit is broken through said electro-magnet and to be released from said slide when the circuit is closed, and a make-and-break device inserted in said circuit at the other station.

20 screen in said circuit at each station.

5. A device of the character described, consisting of an electrical circuit between two stations, an electro-magnet inserted in said circuit at one station, a semaphore-signal device at the same station, a rotatable disk having engaging means thereon and operatively connected with said semaphore-signal device, a slide adapted to lock into said engaging means when in a predetermined position, an armature-stop actuated by said electro-magnet and adapted to hold said slide in a desired position when said circuit is broken and to be disengaged therefrom when the circuit is closed, and make-break devices inserted in said circuit at each station.

each station.

6. A device of the character described, consisting of an electrical circuit between two stations, an electro-magnet inserted in said circuit at one station, a semaphore-signal device at the same station, a rotatable disk having engaging means thereon and operatively connected with said semaphore-signal device, a slide adapted to lock into said engaging means when in a predetermined position, an armature-stop actuated by said electro-magnet and adapted to hold said slide in a desired position when said circuit is broken and to be disengaged therefrom when said circuit is closed, a record-slip, a recording-device operatively connected to said slide and adapted to make a record on said slip when the slide is disengaged from said disk, and a make-and-break device inserted in said circuit at the other station.

7. A device of the character described, consisting of an electrical circuit between two stations, an electro-magnet inserted in said circuit at one station, a semaphore-signal device at the same station, a rotatable disk having engaging means thereon and operatively connected with said semaphore-signal device, a slide adapted to lock into said engaging means when in a predetermined position,

an armature-stop actuated by said electromagnet and adapted to hold said slide in a desired position when said circuit is broken and to be disengaged therefrom when said circuit is closed, a record-slip, a recording-device, means on said disk adapted to contact with said recording-device and cause the latter to make a record on said slip when the disk is rotated, and a make-and-break device inserted in said circuit at the other station. 75

8. A device of the character described, consisting of an electrical circuit between two stations, an electro-magnet inserted in said circuit at one station, a semaphore-signal device at the same station, a rotatable disk having engaging means thereon and operatively connected with said semaphore-signal device, a slide adapted to lock into said engaging means when in a predetermined position, an armature-stop actuated by said electro-magnet and adapted to hold said slide in a desired position when said circuit is broken and to be disengaged therefrom when said circuit is closed, a record-slip, a recording-device operatively connected to said slide and adapted to make a record on said slip when the slide is disengaged from said disk, another recording-device, means on said disk adapted to contact with the latter recording-device and cause it to make a record on said slip when the disk is rotated, and a make-and-break device inserted in said circuit at the other station. 80 85 90 95

9. A device of the character described, consisting of an electrical circuit between two stations, an electro-magnet inserted in said circuit at one station, a semaphore-signal device at the same station, a rotatable disk having engaging means thereon and operatively connected with said semaphore-signal device, a slide adapted to lock into said engaging means when in a predetermined position, an armature-stop actuated by said electro-magnet and adapted to hold said slide in a desired position when said circuit is broken and to be disengaged therefrom when said circuit is closed, a record-tape, tape-engaging means contacting with said tape and operatively connected with said slide and adapted to move said tape a desired distance when the slide is moved into engagement with the engaging means on said disk, a recording-device operatively connected to said slide and adapted to make a record on said tape when the slide is disengaged from the disk, and a make-and-break device inserted in said circuit at the other station.

- means when in a predetermined position, an armature-stop actuated by said electro-magnet and adapted to hold said slide in a desired position when said circuit is broken and 5 to be disengaged therefrom when said circuit is closed, a record-tape, tape-engaging means contacting with said tape and operatively connected with said slide and adapted to move said tape a desired distance when the 10 slide is moved into engagement with the engaging means on said disk, a recording-device, means on said disk adapted to contact with said recording-device to cause the latter to make a record on said tape when the disk is 15 rotated, and a make-and-break device inserted in said circuit at the other station.
11. A device of the character described, consisting of an electrical circuit between two stations, an electro-magnet inserted in said 20 circuit at one station, a semaphore-signal device at the same station, a rotatable disk having engaging means thereon and operatively connected with said semaphore-signal device, a slide adapted to lock into said engaging 25 means when in a predetermined position, an armature-stop actuated by said electro-magnet and adapted to hold said slide in a desired 30 position when said circuit is broken and to be disengaged therefrom when said circuit is closed, a record-tape, said tape being divided 35 and marked into a predetermined number of spaces of equal length, tape-engaging means contacting with said tape and operatively connected with said slide and adapted to move said tape through one of the said equal 40 spaces whenever said slide is moved into engagement with said disk, means for making a record on one of the said equal spaces on said tape when either the slide is moved out of engagement with the disk or when the disk is 45 rotated, and a make-and-break device inserted in said circuit at the other station. 100
12. A device of the character described, consisting of an electrical circuit between two stations, an electro-magnet inserted in said circuit at one station, a semaphore-signal device at the same station, a rotatable disk having engaging means thereon and operatively 50 connected with said semaphore-signal device, a slide adapted to lock into said engaging means when in a predetermined position, an armature-stop actuated by said electro-magnet and adapted to hold said slide in a desired 55 position when said circuit is broken and to be disengaged therefrom when said circuit is closed, a record-tape, tape-engaging means contacting with said tape and operatively 60 connected with said slide and adapted to move said tape a desired distance when the slide is moved into engagement with said disk, means for making a record on said tape when either the slide is moved out of engagement with said disk or when said disk is 65 rotated, and a make-and-break device inserted in said circuit at the other station. 110

tated, shearing-devices both above and below said recording devices and adapted to sever said tape and prevent its withdrawal from the surrounding casing by the exercise of any other force thereon than that derived from 70 said tape-engaging means, a casing inclosing said tape and said recording devices, and a make-and-break device inserted in said circuit at the other station.

13. A device of the character described, 75 consisting of an electrical circuit between two stations, an electro-magnet inserted in said circuit at one station, a semaphore-signal device at the same station, a rotatable disk having engaging means thereon and operatively 80 connected with said semaphore-signal device, a slide adapted to lock into said engaging means when in a predetermined position, an armature-stop actuated by said electro-magnet and adapted to hold said slide in a desired 85 position when said circuit is broken and to be disengaged therefrom when said circuit is closed, a record-tape, said tape being divided and marked into a predetermined number of 90 spaces of equal length, tape-engaging means 95 contacting with said tape and operatively connected with said slide and adapted to move said tape through one of the said equal spaces whenever said slide is moved into engagement with said disk, means for making a record on one of the said equal spaces on said tape when either the slide is moved out of engagement with the disk or when the disk is rotated, and a make-and-break device inserted in said circuit at the other station. 100

14. A device of the character described, consisting of an electrical circuit between two stations, an electro-magnet inserted in said circuit at one station, a semaphore-signal device at the same station, a rotatable disk having engaging means thereon and operatively connected with said semaphore-signal device, a slide adapted to lock into said engaging means when in a predetermined position, an armature-stop actuated by said electro-magnet and adapted to hold said slide in a desired 110 position when said circuit is broken and to be disengaged therefrom when said circuit is closed, a record-tape, tape-engaging means contacting with said tape and operatively 115 connected with said slide and adapted to move said tape a desired distance when the slide is moved into engagement with said disk, means for making a punctured record on said tape when either the slide is moved out of engagement with said disk or when said disk is 120 rotated, a casing entirely inclosing said tape and said recording means, a conduit adapted to convey out of said casing the clippings from the punctured tape, and a make-and-break 125 device inserted in said circuit at the other station.

15. A device of the character described, consisting of an electrical circuit between two stations, an electro-magnet inserted in said 130

circuit at one station, a rotatable disk having engaging means thereon and operatively connected with a semaphore-signal device, a semaphore-signal device at the same station 5 operatively connected with said rotatable disk, a slide adapted to lock into said engaging means when in a predetermined position, an armature-stop actuated by said electromagnet and adapted to hold said slide in a 10 desired position when the circuit is broken and to be disengaged therefrom when the circuit is closed, a record-slip, means for making a record on said slip when either the slide is

moved out of engagement with said disk or when said disk is rotated, means for preventing rotation of said disk in one direction, and a make-and-break device inserted in said circuit at the other station. 15

Signed at Waterloo, Iowa, this 7th day of May 1907.
